United States Patent Office.

RUSSEL FRISBIE, OF CROMWELL, CONNECTICUT, ASSIGNOR TO J. AND E. STEVENS & CO., OF SAME PLACE.

Letters Patent No. 61,729, dated February 5, 1867.

CAST-IRON FRAMES FOR TOY LOOKING-GLASSES.

The Schedule referred to in these Letters Patent and making part of the same.

TO ALL WHOM IT MAY CONCERN:

Be it known that I, RUSSEL FRISBIE, of Cromwell, in the county of Middlesex, and State of Connecticut, have invented a new and improved Mode of Fastening the Glass in the Cast-Iron Frame of a Toy Looking-Glass; and I do hereby declare that the following is a full and exact description thereof, reference being had to the accompanying drawings, and to the letters of reference marked thereon.

The nature of my invention consists in casting into the back of the cast-iron frame of a toy looking-glass, near the edge of the frame, at the same time that the frame is cast, three pieces, one on each side of the frame near the top of it, and one at the bottom of the frame, midway, of tin, sheet iron, or any cheap metals that will not melt upon the liquid iron's coming in contact with them in the process of casting, of about one-fourth of an inch square, and thin enough so that they can be easily bent down against the glass and at the same time form a secure fastening for the glass when it is in its place in the frame. When the glass is put in its place in the frame, these pieces of metal are pressed down with ease upon the glass, and thus form a secure fastening for it.

To enable others skilled in the art to make and use my invention, I will proceed to describe its construction and operation.

I mould my frame after any of the known patterns, in sand, and before pouring the liquid iron into the mould, I place these pieces of metal or fasteners in the sand of which the mould is composed, at those points where I wish to fasten them into the frame, leaving a little part of each out of the sand, enough so that they may be fastened firmly in the frame, and then I pour into the mould the melted iron, which surrounds the parts of the fasteners left out of the sand; and as the iron cools, these pieces of metal or fasteners become firmly fixed in the frame. These pieces of metal or fasteners are about one-fourth of an inch wide and a little more than one-fourth of an inch long. Figure 2, in the drawing, represents one of them. These pieces of metal may consist of tin, sheet iron, or any cheap metals that will not melt upon the liquid iron's coming in contact with them in the process of casting, and thin enough so that they may be easily bent down, and at the same time form a secure fastening for the glass. Figure 1 of the drawings represents a frame with these pieces of metal or fasteners in it. The pieces are represented by A, B, and C in the drawing. These pieces or fasteners are cast into the frame at such an angle that the glass can be conveniently put in its place in the frame, (letters A and B in the drawing represent two fasteners as they are cast into the frame,) and when the glass is placed in the frame, the pieces or fasteners are pressed down upon the glass, as represented by letter C in the drawing, which is a third fastener bent down in the manner for fastening the glass, and when bent or pressed down they form a secure and a cheap fastening for the glass. I use three in each frame, but more may be used if desirable.

What I claim as my invention, and desire to secure by Letters Patent, is—

The fastening of the glass into the cast-iron frame of a toy looking-glass, by means of small pieces of tin sheet iron, or other suitable metal cast into the edge of the frame, as herein described.

RUSSEL FRISBIE.
